US00D752202S

(12) **United States Design Patent**
Berkman et al.

(10) **Patent No.:** US D752,202 S
(45) **Date of Patent:** ** Mar. 22, 2016

(54) **FAN GRILLE**

- (71) Applicant: **Homewerks Worldwide, LLC**,
Lincolnshire, IL (US)
- (72) Inventors: **Peter D. Berkman**, Highland Park, IL
(US); **Ruilin Zhang**, Foshan (CN);
Jeffrey Jon Pischke, Cary, IL (US);
Michael Malaker, Gurnee, IL (US)
- (73) Assignee: **Homewerks Worldwide, LLC**,
Lincolnshire, IL (US)
- (**) Term: **14 Years**

(21) Appl. No.: **29/475,728**(22) Filed: **Dec. 5, 2013****Related U.S. Application Data**

- (63) Continuation-in-part of application No. 13/962,625, filed on Aug. 8, 2013.
- (51) **LOC (10) Cl.** **23-04**
- (52) **U.S. Cl.**
USPC **D23/412**
- (58) **Field of Classification Search**

Primary Examiner — Susan Bennett Hattan
Assistant Examiner — Marie Fast Horse

(74) *Attorney, Agent, or Firm* — Cozen O'Connor**CLAIM**

We claim the ornamental design for a fan grille, as shown and described.

DESCRIPTION

FIG. 1 is a perspective view of a fan grille showing our new design;

FIG. 2 is a bottom plan view thereof; and,

FIG. 3 is a side elevation view thereof.

The broken lines immediately adjacent to the shaded area represent unclaimed boundaries of the design.

1 Claim, 2 Drawing Sheets# US D752,202 S
